UNITED STATES PATENT OFFICE.

ROY S. HOPKINS, OF FAIRMONT, WEST VIRGINIA.

INSULATOR.

1,206,846.

Specification of Letters Patent.

Patented Dec. 5, 1916.

Application filed January 14, 1916. Serial No. 72,099.

To all whom it may concern:

Be it known that I, ROY S. HOPKINS, a citizen of the United States, residing at Fairmont, in the county of Wood and State 5 of West Virginia, have invented certain new and useful Improvements in Insulators, of which the following is a specification.

My invention relates to an insulator for use on telephone and telegraph lines and has 10 for its object to provide means whereby the line can easily be broken for testing purposes and as easily restored after the test has been made.

My device comprises an insulator having 15 a mercury well in its top, of the kind described in my prior application Serial Number 44,088, filed August 6, 1915, into which well are dipped the bent ends of the line wires.

20 My present invention has for its object to provide a means whereby the ends of these line wires are positively held in the mercury cup while at the same time this holding device permits the ready removal 25 of the wires from the well.

It has for its further object to provide a holding device which shall be permanently connected to one of the wires so that while 30 readily adjusted into either the holding or disconnecting position, it is still not detachable from the wire. This feature is of 35 importance because the testing is done by a lineman upon these insulators usually located on the tops of poles and under varying conditions of wind and weather; and my device is particularly designed to have no detachable parts which can be dropped or lost. This holding device further forms a protective cover for the mercury well.

40 The invention will be readily understood from the accompanying drawing, in which—

Figure 1 is an elevation of the insulator provided with my connecting and holding device; Fig. 2 is a top plan view and Fig. 45 3 is a bottom plan view of the holding device shown in Fig. 1; Fig. 4 is a cross-section showing the mercury cup in the top of the insulator; and Fig. 5 is a horizontal section through Fig. 4; Fig. 6 shows a modified 50 form of mercury cup; Fig. 7 is a section through a modified form of holding device; and Fig. 8 is a bottom plan view of the holding device shown in Fig. 7; Fig. 9 is an elevation of a modified form of insulator, provided with a holding device attached di-

rectly thereto; Fig. 10 is a sectional view of a modification.

Referring to the drawings, A is an insulator, preferably of glass or porcelain and provided with the usual two external grooves 60 in which are located the line wires D and E. The end portions of these line wires are curved upwardly and have at their ends right angular bends, these bent ends extending into a mercury cup C, at the top of the 65 insulator. As shown in Fig. 4, this cup C has at its top an annular flange F, the flange being spaced away from the body of the insulator sufficiently to permit the passage thereunder of the flanges G, G of the holding device H. As shown in Figs. 1, 2 and 3, this holding device is made of a single piece of sheet metal having the inwardly-turned flanges G, G formed near its central portion and having at one end an extension I 70 preferably curved to act as a thumb-piece; and having at its other end a bent extension K having two perforations therein through which the wire E passes.

The mercury cup C may be secured in the 75 cavity in the insulator, as shown in Figs. 4 and 5, by corrugating longitudinally its lower tubular portion, and forcing the corrugated tubular portion into the opening in the insulator.

The operation of the device, as thus far described, is as follows:—In order to break the line for testing purposes, the lineman presses down upon the thumb-piece I, or upon the body of the holding device H, and slides it to the left, thereby leaving the ends of the wires free to be removed from the mercury cup, while at the same time the holding device is itself held on the wire E with no possibility of detachment. In order to restore the line connection, the bent ends of the line wires are inserted into the mercury cup and the holding device H is slid to the right, its inturned flanges G, G 85 extending under the edges of the annular flange F, thereby positively securing the two ends of the wires in their proper position in the mercury cup.

In Fig. 6 is shown another method of connecting the mercury cup to the insulator. 105 In this case the tubular portion of the cup C' is corrugated transversely, instead of longitudinally as in Fig. 4, and may be secured in place either by a driving-fit or by pouring melted sulfur L into a space left be- 110

tween the tubular portion and the wall of the cavity in the insulator.

In Figs. 7 and 8 is shown a modified form of holding device H' , provided with inwardly turned flanges G' , G' , a thumb-piece I' at one end of the holding device, and an extension K' , at the other end, formed by bending the sheet metal into a closed tube to loosely embrace the wire E . The operation of this form of device is the same as that of the similar device already described.

In Fig. 9, I have shown a modified form in which the insulator A' is provided at its top with an annular flange F'' , beneath which is a groove portion in which the correspondingly curved flanges G'' , G'' , of a holding device H'' may be seated. This holding device may be of either of the forms above described, and is intended to operate in a similar manner.

In Fig. 10 I have shown still another form of holding device H'' which is, at its central portion, provided with an upwardly projecting hollow boss M , in which is mounted a screw N having at its bottom a wedge-shaped plug O . When the screw N is screwed downwardly as shown in this Fig. 10, the wedge-shaped plug O extends between the line wires D and E and presses them against the metallic cup C'' , thereby making not only a good metallic connection through the line wires and the cup, but also a connection between these wires through the plug O . It will be observed that a good metallic connection between the line wires will thus be made even though no mercury be used in the cup. In order to disconnect

the wires the screw N is moved up into the cavity of the hollow boss M and the holding device H'' is moved sidewise to disengage the flanges as in the other forms of holding devices above described.

In each of the forms above described it will be noted that the line connection can be readily broken and restored by a simple movement of the holding device; that the holding device is permanently attached to one of the line wires; that the holding device positively holds the ends of the line wire in the mercury cup so that a good connection is certainly made; and that the mercury cup is completely covered against the entrance of rain or dust.

I claim:

1. The combination with an insulator having a cavity in its top of line wires having bent ends adapted to extend into said cavity, and a holding device adjustable on but permanently connected to one of the line wires, the holding device and the insulator being provided with coöperating means for holding the ends of the line wires in the cavity.

2. The combination with an insulator having a cavity in its top of a cup secured in said cavity and having a flange at its top spaced from the top of the insulator, and a holding device comprising a body portion having inwardly-turned flanges adapted for engagement with the flange on the cup, said body portion having an extension provided with means for securing the body portion slidably on a wire.

In testimony whereof I affix my signature.

ROY S. HOPKINS.
